UNITED STATES PATENT OFFICE.

CALVIN G. TURNER, OF WILMINGTON, DELAWARE.

RAILROAD COUPLING DEVICE.

SPECIFICATION forming part of Letters Patent No. 729,813, dated June 2, 1903.

Application filed September 29, 1902. Serial No. 125,155. (No model.)

To all whom it may concern:

Be it known that I, CALVIN G. TURNER, a citizen of the United States of America, residing in Wilmington, in the county of New Castle, in the State of Delaware, have invented a certain new and useful Improvement in Railroad Coupling Devices, of which the following is a true and exact description, reference being had to the accompanying drawings, which 10 form a part thereof.

My invention relates to couplers for railway-vehicles, and has for its object to provide improved means for coupling such vehicles on short or reversed curves, my invention being especially intended and adapted for application to switching-engines.

The nature of my improvements will be best understood as described in connection with the drawings, in which they are illustrated, and in which—

Figure 1 is a front view of my improved coupling device with the coupling-head removed; Fig. 2, a plan view of the coupling device in what I believe to be its best form 25 with the coupling-head shown in dotted lines. Fig. 3 is a cross-sectional view on the line 3 3 of Fig. 2, and Fig. 4 is a side elevation of one of the locking-hooks which are preferably used in connection with the pivot-beam.

30 A indicates the coupler-beam, which, as shown, is provided with braces A', by which it is secured to the end of the switching-engine.

B B are cast heads secured on the end of 35 the beam and of usual form, except that they are shown as provided with a curved bearing, (indicated at B'), over which a wire rope can readily move.

C is a pivot-bearing attached to the center 40 of the beam A. As shown, C' C' are pivot-bearings attached to the side of the beam A.

D D' D' represents a beam built up, as shown, of a front plate D, secured to horizontal top and bottom plates D' D' by proper braces, the top 45 and bottom plates D' D' having the approximately triangular shape shown and carrying at their inner taper parts the pivot-bearings d d', through which and the pivot-bearing C the pivot-pin passes. To the top and bottom 50 of the beam D D' D' are secured the guideways, (indicated at D² D²), and the top plate of the beam is provided with latching-notches,

as indicated at D³ D³, while the ends of the beam, as illustrated, are provided with eyes D⁴ D⁴.

55 E E are guide-pulleys secured on the rear side of the beam A.

F is a wire rope secured to the eyes D⁴ D⁴ and passing back over the rounded surface B' of the heads B B and over the pulleys E E, as shown. This wire rope serves simply the purpose of a guard to keep operatives from getting between the beams D D' and A.

G G are hook-levers pivoted on the pivot-bearing C' and having downwardly-pointed 65 hooked ends G', which are adapted to engage in the latch-notches D³ and which when so engaged hold the pivot-beam D D' in fixed relation and position to the beam A.

H is a sliding head having inwardly-turned 70 ends H' H', which extend above and below the guideways D² D², while hooked ends H² H² engage behind said guideways, thus securing the head D firmly to the beam D D', while permitting it to slide freely in either 75 direction thereon.

I, Fig. 2, indicates a coupling-head which is, as shown, pivotally secured to the perforated bearings of the head H, which are indicated at H³.

80 It will be seen that the head H, carrying the coupling-head, is by my construction free to slide, if necessary, from end to end of the beam D D', which freedom gives a great range of operation to the coupling-head and enables 85 such couplings to be made under conditions which with ordinary constructions will be impracticable. My construction not only enables such couplings to be made, but permits the coupling-head to adapt itself to changed conditions with the greatest ease, owing to the freedom of the head H to slide on the guideways.

80 It will also be obvious that a further and much greater facility for coupling under difficult conditions is afforded by the pivotal connection of the beam carrying the guideways with the vehicle, while the pivot-beam carrying the guideways can be secured in fixed position on the vehicle by the engagement of the hooked arms G with the pivotal beam.

Having now described my invention, what I claim as new, and desire to secure by Letters Patent, is—

1. As a coupling device, a guideway adapted to extend transversely across the end of a railway-vehicle, in combination with a head secured on said guideway so as to extend in front of the guideway and to slide transversely thereon, and a coupler secured to said sliding head.
2. As a coupling device, a guideway adapted to extend transversely across the end of a railway-vehicle, in combination with a head secured on said guideway so as to extend in front of the guideway and to slide transversely thereon, and a coupler pivotally secured to said sliding head in front of the guideway.
3. As a coupling device a beam adapted to

be pivotally secured at its center to the end of a railway-vehicle in combination, with a guideway secured on said beam, a sliding head secured on said guideway and a coupling-head secured to the sliding head.

4. As a coupling device, a beam adapted to be pivotally secured at its center to the end of a railway-vehicle in combination, with a guideway secured in said beam, a sliding head secured on said guideway and a coupling-head pivotally secured to the sliding head.

CALVIN G. TURNER.
